UNITED STATES PATENT OFFICE.

GARTH G. GILPIN, OF RIVERSIDE, ILLINOIS, ASSIGNOR TO WALTER P. MURPHY, OF NEW YORK, N. Y.

CORRUGATED SHEET-METAL DOOR FOR RAILWAY CARS OF THE DUMPING TYPE.

Application filed November 14, 1919. Serial No. 397,907.

To all whom it may concern:

Be it known that I, GARTH G. GILPIN, a citizen of the United States, residing at Riverside, in the county of Cook and State, of Illinois, have invented certain new and useful Improvements in Corrugated Sheet-Metal Doors for Railway Cars of the Dumping Type, of which the following is a specification.

10 My invention relates to the construction of railway freight cars of the dumping type and has for its principal object to provide an improved sheet metal door for cars of this type, more especially for cars known 15 as "general service" cars, (intended to serve as ordinary gondola cars for the transportation of miscellaneous freight, as well as bulk loads that can be dumped) having reinforcing ribs or corrugations so 20 formed that the corrugations provide maximum strength and rigidity to the body and marginal portions of the door.

25 My invention provides an improved reinforced door of the above character having corrugations which are pressed so that they project alternately above and below the original plane of the sheet. Certain of the corrugations are made relatively long so as to extend close to the margins of the door 30 to provide maximum rigidity. The configurations of the corrugations and marginal portions of the sheets are such that water will freely drain from the depressed corrugations. The upwardly projecting 35 corrugations are so formed that their crests are substantially flush with the flooring of the car when the door is closed. When a car, having doors of this construction, is loaded with articles, such as rails, machinery, or the like, these articles will not be supported entirely by the doors of the car, but will be supported in part by the cross framing and other parts of the flooring of the car.

45 The invention consists in the novel and improved arrangement and construction of parts, to be hereinafter described and claimed, for carrying out the above stated objects and such other incidental objects as 50 will appear from the following description.

My invention is illustrated in a preferred embodiment of the accompanying drawings, wherein

55 Fig. 1 is a plan view of a door panel formed in accordance with my invention.

Fig. 2 is a sectional view on line 2—2 of Fig. 1, showing the doors operatively connected to the under-framing of the car body.

Fig. 3 is a detail sectional plan showing 60 the attachment of a reinforcing member to the flange of the door sheet.

Fig. 4 is an end elevation of the door with part of the car in section.

Figs. 5, 6 and 7 are sectional views on 65 lines 5—5, 6—6, and 7—7 of Fig. 1, and

Fig. 8 is a side elevation of the door with portions in section.

Like characters of reference designate 70 like parts in the several figures of the drawings.

Referring to the drawings, 10 indicates the center sill of a car of the general service type, and 12 the side sheathing. It will be understood that the car under-framing, 75 as is customary in cars of this general type, is constructed with the usual cross-bearers 14 and the flooring provided with a number of dumping openings on opposite sides of the center sill, these openings being normally closed by hinged bottom sections or 80 doors which are manipulated by apparatus which forms no part of the present invention and which, therefore, has been omitted from the drawings. This invention concerns the construction of a door suitable for use in a car of this type, or 85 with dumping cars where similar conditions prevail.

The door consists of a sheet metal panel 90 46, preferably, although not necessarily, composed of a single sheet of metal. The door sheet, as it may be termed, is hinged to the center sill 10 (the hinges being indicated at 49). The end marginal portions 56, 95 57 of the door sheet and the side marginal portion 55 thereof which bears against the under side of the inturned part of the side sheet 12 are in the same plane and are preferably formed with downturned rigidifying 100 flanges. The door panel 46 is reinforced by a pair of Z-bars 47, 48 on the under side of the corrugated plate, these Z-bars running in the direction transverse to the corrugations and being located near the ends of the 105 same so as to stiffen the panel longitudinally of the car so as to prevent sagging under the load. The hinge straps 49 are preferably attached by rivets 50 to the Z-bar 48. Either or both of the Z-bars may be kept from 110

- tating by suitable restraining devices. I have shown the Z-bar 47 as restrained at substantially its middle point by a short strap or bracket 51 of Z-section riveted to the door panel at 52 and to the Z-bar 47 at 53. That is, the center portion of the Z-bar is in effect given a channel formation at its center. The door panel is formed with corrugations 54, which project above the original plane of the panel, the plane of the marginal portions 55, 56, 57, so that their crests are substantially flush with the flooring of the car when the door is closed and have an alternating arrangement with corrugations 58 depressed below the original plane of the sheet. All of the upstanding corrugations except the two at opposite ends of the door, which have been designated 54^a, extend at the side of the margin 55 beyond the Z-bar 47, as indicated at 59, while the depressed corrugations 58 and the end upstanding corrugations 54^a terminate short of the place where the Z-bar 47 is attached to the sheet. The marginal portion 60 on the hinged side of the door is pressed down below margins 55, 56, 57 to the level of the bottoms of the depressed corrugations 58. By this arrangement any moisture will drain off along the depressed edge 60 of the panel instead of being trapped, as would be the case, if both ends of the corrugations were below the adjacent uncorrugated margins. The corrugations are made to terminate within the edges of the sheet so that they will give rigidity. The extremities of the marginal portions 56-57 adjacent the center sill are depressed, as indicated at 49^a to the level of the marginal portion 40 of the sheet. This configuration of the sheet adapts it to fit snugly into place under the center sill and side sheets of the car. Preferably the Z-bar 47 is fastened at its extremities to the end flanges 61 of the door panel by means of angular gussets 62 (Fig. 3). By the disposition of corrugations and of reinforcing means just described, the free edge of the door, which is, of course, particularly subject to deflection and warping, is made very rigid.
- 50 I claim:
1. In combination with a railway car having a dumping opening in the bottom, a sheet metal door for closing said opening formed with corrugations which alternately project above and below a flat marginal portion of the door sheet, and a reinforcing element on the under side of the sheet adjacent said marginal portion and lying transversely to said corrugations, the upstanding corrugations extending over said reinforcing element and the depressed corrugations terminating short of the same.
  2. In combination with a railway car having a dumping opening in the bottom, a sheet metal door for closing said opening formed with relatively long corrugations and shorter corrugations disposed in alternating arrangement, a reinforcing member of angular cross section on the under side of the door having a flange attached to the door and a web projecting therefrom, and a retaining device to prevent the tendency of said reinforcing member to rotate on its longitudinal axis.
  3. In combination with a railway car having a dumping opening, a sheet metal door to close said opening formed with a plurality of rigidifying ribs consisting of relatively long ribs and shorter ribs disposed in alternate arrangement across the sheet and terminating within the edges of said sheet, said sheet being formed so that portions of the corrugations project below the plane of the adjacent uncorrugated parts of the sheet while the corrugations at one end are entirely above the uncorrugated marginal part of the sheet adjacent thereto for drainage purposes.
  4. In a railway car of the type described, the combination of the fixed portion of the car bottom constructed to provide a dumping opening, and a hinged door to close said opening formed of a metal sheet having pressed therein relatively long corrugations and shorter corrugations disposed in alternate arrangement, the crests of certain of said corrugations being substantially flush with the upper surface of the fixed portion of the car bottom when the door is in its closed position.
  5. In combination with a railway car having a door opening in the bottom, a sheet metal door to close the same formed with a plurality of corrugations consisting of relatively long corrugations and shorter corrugations disposed in alternating arrangement across the door sheet, the portions of the relatively short corrugations adjacent one of the edges of said sheet projecting below the adjacent marginal parts of the sheet while the opposite ends of the corrugations stand substantially above the uncorrugated part of the marginal sheet adjacent thereto.
  6. The combination with a railway car having door openings in the bottom, a sheet metal door to close the same formed with a plurality of parallel corrugations consisting of relatively long corrugations and shorter corrugations disposed in alternating arrangement and extending across the door sheet between opposite edges at right angles to said edges, the portions of certain of the corrugations adjacent one of said edges projecting below the adjacent marginal parts of the sheet while the opposite ends of the corrugations stand substantially above the uncorrugated part of the marginal sheet adjacent thereto.
  7. In combination with a railway car having a dumping opening in the bottom, a

- sheet metal door to close the same formed with a depressed portion which extends to one edge of the door sheet, said depressed portion having pressed therein corrugations 5 upstanding therefrom which terminate within the edges of the sheet and project beyond the depressed portion of said sheet.
8. In combination with a railway car having a dumping opening in the bottom, a sheet metal door to close the same formed with a depressed portion which extends to one edge of the door sheet, said depressed portion having pressed therein a plurality 10 of upstanding, parallel corrugations at substantially right angles to said edge, which merge into the door sheet at opposite edges, the extremities of the corrugations adjacent one of the edges of the sheet being extended beyond the depressed portion of said sheet.
- 15 9. In combination with a railway car having a dumping opening in the bottom, a sheet metal door to close the same formed with a depressed portion which extends along one edge of the door sheet, said door being formed with corrugations which project above the depressed portion of the door sheet but below the other marginal portion thereof, and corrugations disposed in alternating arrangement with the first mentioned 20 corrugations formed to project above said other marginal portions of the sheet.
10. In combination with a railway car having a dumping opening in the bottom, a sheet metal door to close the same formed with a depressed portion which extends 35 along one edge of the door sheet, leaving marginal portions along the other three edges which are in a higher plane, said sheet being formed with corrugations projecting entirely above the depressed margins thereof and slightly above the plane of said other marginal portions and extending beyond said depressed portions adjacent one edge of the sheet.
11. A door structure for railway cars of 40 the dumping type comprising a sheet metal panel having marginal portions formed with rigidifying flanges one marginal portion of which is depressed below the other margins and a plurality of rigidifying corrugations 45 extending across the sheet at right angles to said depressed margin and comprising relatively long corrugations and shorter corrugations disposed in alternate alignment.
12. A door structure for railway cars of 50 the dumping type comprising a sheet metal panel provided with rigidifying marginal portions and relatively long rigidifying ribs and shorter ribs disposed in alternate arrangement across the sheet.

GARTH G. GILPIN.
